(57) **CLAIM**

The ornamental design for a vehicle bumper trim, as shown and described.

DESCRIPTION

FIG. 1 depicts a front, top, left perspective view of a vehicle bumper trim showing our new design.

FIG. 2 depicts a front, top, right perspective view thereof.

FIG. 3 depicts a front view thereof.

FIG. 4 depicts a back view thereof.

FIG. 5 depicts a left side view thereof.

FIG. 6 depicts a right side view thereof.

FIG. 7 depicts a top view thereof; and,

FIG. 8 depicts a bottom view thereof.

The dot-dash lines depict boundaries of the claimed design.
The even dash lines depict portions of the article forming no
part of the claimed design.

1 Claim, 7 Drawing Sheets
